LOUIS M. PLANSOEN, OF GARFIELD, NEW JERSEY.

CONTROLLING AND ALARM DEVICE.

1,205,661.

Specification of Letters Patent. Patented Nov. 21, 1916.

Application filed June 5, 1915. Serial No. 32,338.

To all whom it may concern:

Be it known that I, LOUIS M. PLANSOEN, a subject of the Queen of the Netherlands and a resident of Garfield, in the county of Bergen and State of New Jersey, have invented a new and Improved Controlling and Alarm Device, of which the following is a full, clear, and exact description.

The invention relates to paper-making machines of the Fourdrinier type, and its object is to provide a new and improved controlling and alarm device located at the delivery end of the endless wire screen or apron and arranged to shift the delivery end of the screen back to normal position in case of a deflection and at the same time sound an alarm for the attendant to manipulate the usual hand guide roll at the other end of the machine.

20 In order to accomplish the desired result, use is made of means controlled by the screen and connected with a guide roller over which passes the screen to move the guide roller and the screen bodily in a transverse and longitudinal direction on a deflection of the screen.

A practical embodiment of the invention is represented in the accompanying drawings forming a part of this specification, in which similar characters of reference indicate corresponding parts in all the views.

Figure 1 is a side elevation of the controlling and alarm device as applied; Fig. 2 is an enlarged side elevation of the same; Fig. 3 is a plan view of the same; Fig. 4 is a transverse section of the same on the line 4—4 of Fig. 2; Fig. 5 is a sectional side elevation of a portion of the shifting means for the guide roller bearing; Fig. 6 is a transverse section of the toothed wheel and double pawl for actuating the toothed wheel; Fig. 7 is an enlarged face view of one of the guides for the circuit closing rods, the insulation being shown in section; Fig. 8 is a diagrammatic view of the electric alarm; and Fig. 9 is a side elevation of a modified form of the electric alarm.

The endless wire screen or apron A of usual construction is mounted to travel in the direction of the arrow a' and at its delivery end passes around the usual roll B, and near the said delivery end it passes over a guide roller C. The shaft C' of this guide roller C is journaled at each end in a bearing D mounted to slide on a guideway E formed on a bracket E' attached to the main

frame F of the Fourdrinier machine and disposed obliquely relatively to the axis of the guide roller C, as plainly indicated in Fig. 3. In the bearing D is mounted to 60 turn a nut G (see Fig. 5) screwing on a screw rod H attached at its ends on arms E² forming part of the bracket E'. On the nut G is secured or formed a bevel gear wheel G' in mesh with a bevel gear wheel I' 65 attached to or formed integrally on the back of a wheel I having internal teeth I², as plainly illustrated in the drawings.

The teeth I² of the wheel I are adapted to be engaged by either end of a double 70 pawl J having a pivot J' journaled in an arm K mounted to swing loosely on a stud K' secured to the front of the bearing D and on which stud K' turns loosely the wheel I (see Fig. 4). The arm K is piv- 75 otally connected by a link L with a crank pin L' held on the end of the shaft C' of the guide roller C so that when the latter is rotated the crank pin L' and the link L impart a continuous rocking motion to 80 the arm K. Now as long as the pawl J is in the normal inactive position shown in Fig. 2, that is, with both ends out of engagement with the teeth I², then the wheel I remains at a standstill, but when the pawl 85 J is tilted in either direction the then uppermost end engages the teeth I² to turn the wheel I in the corresponding direction. The rotary motion of the wheel I is transmitted by the gear wheels I' and G' to the 90 nut G screwing on the rod H and held in the bearing D so that the latter is shifted on the guideway E either to the left or to the right according to the direction in which the wheel I is turned at the time. 95

The tilting of the pawl J is controlled by the screen or apron A on the deflection thereof in a lateral direction, and for this purpose the following arrangement is made: On the pivot J' of the pawl J is secured a 100 downwardly extending arm N in the lower end of which is mounted to turn an eye N' through which extends loosely a rod O provided on opposite sides of the eye N' with springs O', O² abutting against collars O³, 105 O⁴ attached to the rod O. The rod O is slightly inclined and its upper end O⁵ is provided with a screw thread on which screw nuts O⁶, O⁷ engaging opposite sides of a bell crank lever P fulcrumed on the pivot 110 P' attached to the arm E³ of the bracket E'. The bell crank lever P is pivotally connected

with a transversely extending bar Q passing under the upper run of the apron or screen A immediately in front of the roller C. The bar Q is mounted to slide transversely in suitable bearings on an arm E⁴ forming part of the bracket E' and the said bar is provided with lugs Q' (one only being shown) held adjustably on the bar by set screws Q². The lugs Q' engage the side edges of the apron A so that when the latter is deflected in a transverse direction then movement is given to the bar Q in a like direction whereby the bell crank lever P is caused to swing and the rod O is caused to impart a swinging motion to the arm N to rock the pawl J so that one end thereof engages the teeth I². As the arm K is continually rocked by the rotating shaft C' of the guide roller C it is evident that when the pawl J is in engagement with the teeth I² a turning movement in one direction is given to the wheel I for shifting the bearing D on the guideway E, as previously explained. When this takes place the guide roller C is shifted in a transverse direction and likewise in a longitudinal direction forward or backward according to the movement given to the bearing D.

Presuming that the screen or apron A is deflected from its normal path in the direction of the arrow b' (see Fig. 3) then the sliding movement given to the bar Q causes a rocking of the lever P and a similar movement of the arm N to swing the left-hand end of the pawl J into engagement with the teeth I² of the wheel I to turn the latter in the direction of the arrow a' (see Fig. 2). The rotary motion of the wheel I now causes the nut G to turn to shift the bearing D from the right to the left on the guideway E thus moving the guide roller C in the direction of the arrow b', that is, in the direction in which the apron A is deflected. In case the apron A is deflected in the inverse direction of the arrow b' then the pawl J is turned so that its right-hand end engages the teeth I² of the wheel I to turn the latter in the inverse direction of the arrow c' thus causing the bearing D to travel from the left to the right whereby the roller C is moved bodily in the inverse direction of the arrow b'.

In order to notify the attendant of the Fourdrinier machine that the screen or apron A has deflected, use is made of an alarm for the attendant to manipulate the usual guide roll at the other end of the screen to correct the deflection thereof at its starting end. For the purpose the following arrangement is made: On opposite sides of the wheel I are arranged contact rods R, R' mounted to slide in guideways S, S' of insulating material and attached to the guideway E and the frame F, respectively, as plainly shown in Fig. 2. The rods R, R'

are connected by circuit wires T, T' with one pole of a battery T² connected at its other pole by a circuit wire T³ with an alarm T⁴ of any approved construction and preferably attached to the frame F. The return wire T⁵ of the battery T² is connected with the rod O and consequently electrical connection is had by way of the several parts with the wheel I. Now when the bearing D is moved from the right to the left, as previously explained, the wheel I moves with it in the same direction and finally engages the rod R thus closing the circuit for the alarm T⁴ to sound the alarm. In a like manner when the bearing D is moved from the left to the right, the wheel I moves into engagement with the rod R' to close the circuit and to sound the alarm T⁴. The rods R and R' are adjustably held in their bearings S, S' and for this purpose the outer end R² of each rod R, R' is provided with a screw thread on which screws a nut R³ abutting against the outermost bearing S or S'. A spring R⁴ is coiled on each rod R, R' intermediate the corresponding bearings S and S', S', and one end of the spring R⁴ rests against the outer bearing S or S' and the other end of the spring abuts against a nut R⁵ screwing on the rod R or R'. The springs R⁴ pull the rods R, R' toward the wheel I but the movement in this direction is limited by the nuts R³ abutting against the corresponding bearings S, S', and when the wheel I has moved to the right or to the left then it pushes the corresponding rod R or R' sidewise against the tension of its spring R⁴, and when the wheel I returns to normal position the spring R⁴ returns the corresponding rod R or R' to its normal adjusted position. By adjusting the nuts R³ on the ends R² the rods can be set nearer to or farther from the peripheral face of the wheel I to make contacts sooner or later for closing the circuit whenever the wheel I is shifted to the right or left as previously explained. The contact rods R, R' may be arranged on opposite sides of the shaft C, as shown in Fig. 9, so that when the bearing D, and with it the shaft C, is shifted either to the right or left, then the circuit is closed and the alarm is sounded.

An auxiliary circuit closer is provided which is directly manipulated by the screen or apron A and for this purpose use is made of a transverse bar U mounted to slide transversely in suitable bearings on arms E⁵ arranged on the bracket F'. The bar U is provided with lugs U' adjustably secured to the bar by set screws U² and the said lugs U' engage the edges of the apron A. The ends of the bar U are provided with contact lugs V, V' connected with each other by a circuit wire W also connected with the circuit wire T⁵ of the alarm T⁴. The lugs V and V' are adapted to engage

spring-pressed rods V^2 , V^3 similar to the rod R , R' above described, and connected with each other by a circuit wire W' which is also connected to the circuit wires T , T' and consequently with the battery T^2 . It will be noticed that when the screen or apron A is deflected in the direction of the arrow b' then the bar U is carried along and its contact lug V engages the spring-pressed rod V^2 thus closing the circuit and sounding the alarm T^4 . In a like manner when the screen or apron A is deflected in the inverse direction of the arrow b' then the contact lug V' engages the rod V^3 to close the circuit for sounding the alarm T^4 .

From the foregoing it will be seen that the device controls the guide roller C on any deflection of the screen or apron A and at the same time an alarm is given so that the attendant can quickly manipulate the usual hand guide roll at the starting end of the apron to return the latter to correct position. It is well known that in case the screen or apron A runs off the end of the roll B it is wrinkled or doubled up or otherwise injured and hence its usefulness is practically destroyed. It is also well known that the attendant of a Fourdrinier machine is mostly occupied with the general supervision of the machine and cannot continually watch the correct or incorrect running of the screen or apron A , but when the alarm T^4 is sounded as above described then the attendant can quickly manipulate the hand guide roll to readjust the screen or apron A .

Having thus described my invention, I claim as new and desire to secure by Letters Patent:

1. A controlling device for the guide roller of a screen, comprising shifting means for the said guide roller to move the latter laterally and longitudinally on a deflection of the screen, a normally inactive actuating means for actuating the shifting means, and means controlled by the screen and connected with the said actuating means to render the latter active for shifting the guide roller.

2. A controlling device, comprising a guide roller over which passes a screen, a bearing in which the said roller is journaled, a guideway for the said bearing to slide on and arranged obliquely to the axis of the guide roller, a shifting device for shifting the said bearing on the guideway, whereby the roller will be moved laterally and longitudinally, a driving device for the said shifting device and having a normally inactive member driven continuously from the said guide roller, and a connecting device connecting the screen with the said member to render the latter active on a deflection of the screen.

3. In a paper making machine, the combination of a traveling screen, a guide roller

over which the screen passes, a sliding bearing carrying the roller, means controlled by the screen for shifting the bearing, spring pressed circuit closing members adapted to make contact with a part movable with the roller when said roller is shifted, and an electric alarm connected with the said members.

4. In a paper making machine, the combination of a traveling screen, a guide roller over which the screen passes, a sliding bearing carrying the roller, mechanism controlled by the screen for shifting the said bearing, spring pressed circuit closing rods on opposite sides of a member of the said mechanism and adapted to be engaged by said member when the roller is shifted, and an electric alarm connected with the said rods.

5. In a paper-making machine, the combination of an endless traveling screen, a guide roller over which passes the screen, a bearing for the guide roller, a guideway for the bearing to slide on and arrange obliquely relatively to the axis of the guide roller, a nut turning in the said bearing and provided with a gear wheel, a screw rod mounted to turn and screwing in the said nut, a toothed wheel mounted on the said bearing and having a bevel gear wheel in mesh with the bevel gear wheel on the nut, a rock arm carrying a double pawl adapted to engage the said toothed wheel to turn the latter in either direction, a crank connection between the said rock arm and the guide roller to rock the said arm continually, means connected with the said pawl and with the said screen to throw the pawl into engagement with the toothed wheel on a deflection of the screen, and an electric alarm having two circuit closers controlled by the said toothed wheel to sound an alarm on a deflection of the screen.

6. In a paper-making machine, the combination of an endless traveling screen, a guide roller over which passes the screen, a bearing for the guide roller, a guideway for the bearing to slide on and arranged obliquely relatively to the axis of the guide roller, a nut turning in the said bearing and provided with a gear wheel, a screw rod mounted to turn and screwing in the said nut, a toothed wheel mounted on the said bearing and having a bevel gear wheel in mesh with the bevel gear wheel on the nut, a rock arm carrying a double pawl adapted to engage the said toothed wheel to turn the latter in either direction, a crank connection between the said rock arm and the guide roller to rock the said arm continually, a pawl arm on the pivot of the said pawl, an eye mounted to turn on the said pawl arm, a rod having a sliding engagement with the said eye, springs on the said rod and pressing on opposite sides of the

eye, a bell crank lever connected with the said rod, a shifting bar connected with the said bell crank lever and provided with lugs engaging the edges of the screen to cause the screen to move the shifting bar on a deflection of the screen, spring-pressed circuit closing rods on opposite sides of the said toothed wheel and adapted to be engaged by the toothed wheel, and an electric

alarm connected with the said circuit closing rods.

In testimony whereof I have signed my name to this specification in the presence of two subscribing witnesses.

LOUIS M. PLANSOEN.
